ATTORNEY

UNITED STATES PATENT OFFICE

MARTHA E. JOHNS, OF NORFOLK, VIRGINIA

BAG

Application filed May 27, 1932. Serial No. 614,016.

This invention relates to garment bags and its general object is to provide a bag primarily designed for sleeping garments such as a nightgown or pajamas, that is not only useful as such, but can act in the capacity as a boudoir pillow due to its fanciful design, when the garment is disposed therein.

A further object of the invention is to provide a garment bag of the character set forth, that is simple in construction, inexpensive to manufacture, extremely ornamental, and efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a top plan view of the bag which forms the subject matter of the present invention.

Figure 2 is a bottom plan view thereof.

Figure 3 is a view illustrating the parts of my bag associated and prior to being assembled in bag formation.

Figure 4 is a view illustrating a further step in assembling the same in bag formation.

Figure 5 is a view showing the bag assembled but in open position.

Figure 6 is a side elevation of the bag in closed position.

Referring to the drawing in detail and particularly to Figure 3, it will be noted that my bag is made from a sheet 1 of fabric of any kind of material such as silk, rayon, linen, cotton or the like and the sheet 1 is preferably of rectangular form, with hems 2 arranged at the longitudinal edges thereof.

Threaded in the hems 2 are draw strings 3 and 4 which have their ends free and arranged slightly beyond the hems. The draw strings may be in the form of fancy cord and have tassels or other fancy ornamental articles secured to the ends thereof. 50

Arranged in equi-distantly spaced relation with respect to each other and having one of their ends secured to the sheet 1 in row formation across the longitudinal center thereof are draw strings 5 which are passed through the sheet in running stitch formation so that when the material of the sheet is drawn upwardly on the draw strings 5, ruffles 6 are provided as best shown in Figure 4, and the transverse edges of the sheet 1 are stitched together as at 7 as also best shown in Figure 4. 60

After the ruffles are formed the free ends of the draw strings 5 are disposed within the bag, and the draw string 4 is drawn for disposing the bottom of the bag in gathered formation as best shown in Figure 1. The end portions of the draw string 4 are then tied together, and the end portions may be covered by a bunch of artificial flowers 8 or other ornamental means. 65

From the above description and disclosure of the drawing, it will be obvious that I have provided a bag that may be useful for many purposes, but is primarily designed to accommodate sleeping garments due to its particular formation and when ready for use includes a ruffled portion of substantially conical formation as indicated by the reference numeral 9 and a plain portion of substantially cylindrical formation indicated by the reference numeral 10. The garments are disposed within the bag and the draw string 3 is then drawn and tied as best shown in Figure 2. 75 80 85

When it is desired to arrange the bag in pillow formation the plain and ruffled portions are disposed toward each other to give the effect as shown in Figure 6, with the result 90

the bag not only performs its function as a bag, but also as a pillow.

It is thought from the foregoing description that the advantages and novel features of my 5 invention will be readily apparent.

I desire it to be understood that I may make changes in the construction and in the combination and arrangement of the several parts, provided that such changes fall within 10 the scope of the appended claims.

What I claim is:

1. A bag comprising a single sheet of fabric having its side edges stitched together, hems arranged at the top and bottom of the 15 sheet of material, draw strings arranged in said hems, draw strings having one of their ends secured to the sheet of material and disposed about the bag in row formation, said last mentioned draw strings being passed 20 through the fabric in spaced parallel relation with respect to each other and in running stitch formation whereby to provide a ruffled portion upon movement of the fabric upwardly on the last mentioned draw strings, 25 the first mentioned draw strings being adapted to draw the ends of the sheet together to give a pillow effect with the ruffled portion disposed above the remaining portion of the 30 bag and ornamental means secured to the ruffled portion.
2. A bag of the character described comprising a single sheet of fabric having its side edges secured together, hems arranged at the top and bottom of said sheet, draw strings 35 passed through said hems, draw strings having one of their ends secured to the sheet in row formation across the longitudinal center thereof, said last mentioned draw strings being disposed in spaced parallel relation with 40 respect to each other and passed through the fabric in running stitch formation, said last mentioned draw strings extending through the lower hem and being adapted to provide a ruffled portion forming a part of said bag, 45 the remaining part being plain, the first mentioned draw strings being adapted to draw the top and bottom of the bag together with composite ends of the second mentioned 50 draw strings disposed within said bag, and ornamental means secured to the ruffled portion.

In testimony whereof I affix my signature.
MARTHA E. JOHNS.
